UNITED STATES PATENT OFFICE

2,164,390

JOINT FOR DENTAL BRACKETS

Bert A. Dickerson, Decatur, Ill., assignor to Faries Manufacturing Company, Decatur, Ill., a corporation of Illinois

Application June 10, 1938, Serial No. 212,909

7 Claims. (Cl. 248—282)

My invention relates to the type of devices described in United States Letters Patent No. 1,854,302. As described in that patent, and as found in practice, the users of such brackets desire the greatest possible amount of radial movement, but it is also vitally necessary that such movements cannot in any way twist the electrical conductors which pass through the brackets for that will, in a very short time, chafe the insulation from the wires or actually break them, thus causing a short circuit, with attendant disagreeable results.

My invention has for its principal object to provide a bracket, which will permit the greatest movement of the arms enabling the operator to swing his light into a multiplicity of positions.

A further object is while permitting such motion to render it impossible for the electrical conductors to be twisted or broken, thus avoiding all danger of a short circuit.

A further object is to accomplish the foregoing objects in an exceedingly simple and inexpensive manner, thus making it possible for a wider distribution of these very useful brackets by reason of their lower cost of manufacture.

My means of accomplishing the foregoing objects may be more readily understood by having reference to the accompanying drawings, which are hereunto annexed and are a part of this specification, in which—

Figs. 1 to 5 are more or less diagrammatic views, showing the extent of movement which I have obtained by means of my improved joint;

Fig. 6 is a front elevation of my improvement showing the position of the stops in dotted lines;

Fig. 7 is a vertical sectional view of Fig. 1, some of the parts being shown in elevation;

Fig. 8 is a sectional view taken on line 8—8 of Fig. 7;

Fig. 9 is a partial sectional view taken on line 9—9 of Fig. 7; and

Fig. 10 is a sectional view taken on line 10—10 of Fig. 7.

Similar reference numerals refer to similar parts throughout the entire description.

As shown in the drawings, I provide a central joint formed of a cap 1, and a fitting 2. The cap is cylindrical in shape and closed at its top save for a central opening 3, one side of which has a flat 4 to prevent turning of the screwing means, which consists of a screw bolt 5, provided with a head 6, a threaded portion 7 and a tapered portion 8 adjacent threaded portion 7.

Threaded portion 7 and tapered portion 8 have

a flat side 9, coinciding with the flat 4 in opening 3. The bolt 5 is secured in place by a nut 10.

On the lower edge of cap 1, is cast or formed a downwardly depending lug 11. This lug 11 is fitted to an annular groove 12, formed in the cylindrical fitting 2. The groove however, does not run around the cap for a full three hundred and sixty degrees (360°), but has a stop 13, formed therein which prevents the arm 14 which is threaded into one side of the cap 1, from being swung completely around.

The limit of its movement is clearly shown in Fig. 1.

At the upper end of fitting 2 is a flange 15 which projects and fits into and aligns cap 1 with fitting 2. The bottom of cap 1 abuts flange 16 spaced from flange 15 the central portion forming an annular groove 12.

An arm 17 extends from the fitting 2 an end cap 18 which is of cylindrical shape closed at the top with a central opening 19 therein, to receive one end of the stud 20 which secured the end cap 18 to a plug 21, which closes the lower end of the cap 18. This plug is provided with a central portion 22, which enters the bottom of cap 18 and aligns same with plug 21.

A circumferential flange 23, abuts the end of the wall of cap 18. The flange 23 is spaced from the central portion, forming an annular groove 26, for the reception of a semi-circular projection 25, on the lower end of cap 18.

A stop 24 is placed in the groove 26 to prevent the projection 25 from swinging through a complete circle. An opening 21 is provided in the central portion 22, to afford a passage for the electric wires (not shown). The stud 20, is provided with a threaded end 28 and a tapered portion 29 adjacent the threaded end. Both the threaded and tapered portion have one side flattened similar to bolt 5. A washer 30 having opening 31 with a flat similar to opening 3 and coinciding with the flat on stud 20 prevents the unscrewing of nut 32 when the cap 18 or plug 21 is turned.

At the outer end of arm 14, I mount a cap 33 having an opening 34, in its side which is screwed to the end of arm 14. The moveable joints secured by bolts 5 and stud 20 require a close and fine adjustment so as to allow for the swinging of the bracket without undue play, and is accomplished by drawing the tapered portion on said bolt and stud against the edge of the openings 3 and 19, and locking same in place by nuts 10 and 32.

45

50

55

55

Any desired extension, light or other article can be secured to the cap 33.

It will be clear from an inspection of Figs. 1 to 5 that I afford a wide variety of positions but 5 that at no time can any arm be swung so as to cut off the wires or even chafe the insulation.

Moreover, I attain my objects with minimum of simple and inexpensive parts which can be assembled by ordinary labor, thus materially reducing the labor charge on the brackets. 10

I have illustrated a preferred embodiment of my invention, but I do not wish to limit myself thereto as many changes in the details may be made and yet be within the scope of the herein-after contained claims. 15

Having described my invention, what I regard as new and desire to secure by Letters Patent is:

1. In an articulated bracket having a plurality of arms adapted to be swung to various positions, 20 a central joint connecting the two arms, said joint comprising a cap for one arm, a fitting for the other, interengaging means on their abutting portions, detachable means to hold said portions in engagement, means to prevent said arms swinging through a complete circle, an end cap mounted on the arm secured to the fitting, said end cap comprising a cylindrical portion having a downwardly depending semi-cylindrical flange thereon, a plug which closes said cap, there being an annular groove on said plug which fits said flange, means in said groove to limit the amount of travel of said flange in said recess and a cap on the outer end of the arm fitted to the central cap. 35

2. In an articulated bracket having a plurality of arms adapted to be swung to various positions, a central joint connecting the two arms, said joint comprising a cap for one arm, a fitting for the other, interengaging means on their abutting portions, a screw bolt which extends from the fitting to the cap to hold said lug in said groove, means to prevent said arms swinging through a complete circle, an end cap mounted on the arm, secured to the fitting, said end cap comprising a cylindrical portion having a downwardly depending semi-cylindrical flange thereon, a plug which closes said cap, there being an annular groove on said plug which fits said flange means in said groove to limit the amount of travel of said flange in said groove, means to hold said flange in said recess and a cap on the outer end of the arm fitted to the central cap. 50

3. In an articulated bracket having a plurality of arms adapted to be swung to various positions, a central joint connecting the two arms, said joint comprising a cap for one arm, a fitting for the other, interengaging means on their abutting portions, detachable means to hold said portions in engagement, a stop in said groove which prevents said arms swinging through a complete circle, an end cap mounted on the arm secured to the fitting, said end cap comprising a cylindrical portion having a downwardly depending semi-cylindrical flange thereon, a plug which closes said cap, there being an annular groove on said plug which fits said flange, means in said groove to limit the amount of travel of said flange in said groove, means to hold said flange in said recess and a cap on the outer end of the arm fitted to the central cap. 70

4. In an articulated bracket having a plurality of arms adapted to be swung to various positions, a central joint connecting the two arms, said joint comprising a cap for one arm, a fitting for the other, interengaging means on their abutting portions, a screw bolt which extends from the fitting to the cap to hold said lug in said groove, a stop in said groove which prevents said arms swinging through a complete circle, an end cap mounted on the arm secured to the fitting, said end cap comprising a cylindrical flange thereon, a plug which closes said cap, there being an annular groove on said plug which fits said flange means in said groove to limit the amount of travel of said flange in said groove, means to hold said flange in said recess and a cap on the outer end of the arm fitted to the central cap. 10

5. In an articulated bracket having a plurality of arms adapted to be swung to various positions, a central joint formed of a cap cylindrical in shape and closed at its top save for a central opening, the edge of one side of said opening being flat, a screw bolt fitted to said opening, a threaded portion on said bolt and a tapered portion adjacent the threaded portion, a downwardly depending lug on the lower edge of said cap, a lower cylindrical portion having a peripheral groove in which said lug fits, a stop in said groove to prevent the upper cylindrical cap turning 360°, a central opening in the end of said second-named cylindrical cap in which said bolt fits, there being threaded apertures in said caps for the reception of the arms of the bracket. 20

6. In an articulated bracket having a plurality of arms adapted to be swung to various positions, a central joint connecting the two arms, said joint comprising a cap for one arm, a fitting for the other, interengaging means on their abutting portions, detachable means to hold said portions in engagement, means to prevent said arms swinging through a complete circle, an end cap mounted on the arm secured to the fitting, said end cap comprising a cylindrical portion having a downwardly depending semi-cylindrical flange thereon, a plug which closes said cap there being an annular groove on said plug which fits said flange in said groove to limit the amount of travel of said flange in said groove, means to hold said flange in said recess. 35

7. In an articulated bracket having a plurality of arms adapted to be swung to various positions, a central joint connecting the two arms, said joint comprising a cap for one arm, a fitting for the other, interengaging means on their abutting portions, detachable taper means to hold said portions in engagement, means to prevent said arms swinging through a complete circle, an end cap mounted on the arm secured to the fitting, said end cap comprising a cylindrical portion having a downwardly depending semi-cylindrical flange thereon, a plug which closes said cap, there being an annular groove on said plug which fits said flange, means in said groove to limit the amount of travel of said flange in said groove, taper means to hold said flange in said recess and a cap on the outer end of the arm fitted to the central cap. 50
